UNITED STATES PATENT OFFICE.

WILLIAM WARREN, OF NEWPORT, RHODE ISLAND, ASSIGNOR OF ONE-HALF TO BERNARD RICHARDS, ONE-FOURTH TO WILLIAM WARREN, AND ONE-FOURTH TO CHARLES COHEN, ALL OF NEWPORT, RHODE ISLAND.

POCKET LICENSE CONTAINER OR HOLDER.

Application filed March 10, 1925. Serial No. 14,518.

To all whom it may concern:

Be it known that I, WILLIAM WARREN, a citizen of the United States, and a resident of Newport, in the county of Newport and State of Rhode Island, have made certain new and useful Improvements in Pocket License Containers or Holders, of which the following is a specification:

My present invention relates generally to 10 a pocket container or holder for drivers' licenses, certificates and the like which should be carried upon the person at all times, and my invention has to do more particularly with a holder capable of attachment to a key-ring or key container as well as to a watch chain and the like, so that the owner will be certain to have his driving license or certificate at hand at all times.

20 A further object is the provision of a holder of the above type by which to avoid all danger of loss of the certificate or license therefrom as long as the holder itself remains in connection with the key-ring 25 container or watch chain to which the holder may be attached.

In the accompanying drawing which illustrates my present invention and forms a part of this specification:—

30 Figure 1 is a perspective view illustrating the complete device;

Figure 2 is a vertical longitudinal section taken therethrough, and,

35 Figure 3 is a perspective view illustrating the parts in detached relation.

Referring now to these figures, my invention proposes a holder which comprises in the first instance a cylindrical casing 10 open at both ends and having at one end an 40 inturned flange 11 for a purpose which will be presently described.

Adapted for disposal within the casing 10 is a spindle or stem 12 of substantially reduced diameter with respect to the internal diameter of the casing, so that ample 45 space is left within the casing around the spindle or stem for the disposition of a driver's license, certificate and the like 13, as seen in Figures 2 and 3. At its opposite ends the stem 12 has annularly enlarged 50 heads 14 and 15, the former of which upon insertion of the spindle or stem within the casing, abuts the inturned flange 11 to close the respective end of the casing, and at the

same time prevent further movement of the 55 stem or spindle in the direction in which it is inserted. At the same time the head 15 closes the opposite open end of the casing so that with the parts in this position it is obvious that all danger of loss of the license or certificate 13 from the holder or container is avoided so long as the spindle or stem remains in place.

At one end the spindle stem has a reduced axial extension 16 beyond the head 14, which extension 16 has a diametrical opening 17 and projects through the space circumscribed by the flange 11 when the spindle or stem is in place within the casing for the reception of a split spring ring 18 65 which upon extension through its diametrical opening 17 thus forms a means to prevent withdrawal of the stem or spindle from the casing 10 in the only direction in which it can be withdrawn and which also 70 forms means for convenient attachment of the container or holder as a whole to a key-ring, key-container, watch chain and the like.

It is thus obvious that so long as the container or holder as a whole remains in connection with the key-ring, key container, watch chain and the like to which it may be attached, the split spring ring 18 will remain in engagement with the apertured extension 16 of the stem or spindle, and it follows that so long as this ring does remain in engagement the stem or spindle cannot withdraw from the casing and the latter will continue to be closed against loss 90 of the contents thereof.

My invention thus provides a simple inexpensive device in which the attaching ring and the like forms a two-fold function, and acts as a safety guard, as well as one 95 which may be made of small dimensions and not only attached to a key-ring and the like, but one which is obviously adaptable to exterior embellishment in order that it may serve the ordinary purpose of a 100 charm or pendant in connection with the chain.

I claim:—

A container or holder of the type described including a cylindrical casing open 105 at both ends and having an inturned flange at one end, a spindle or stem movable into and out of the casing through the opposite

end of the latter and having annularly enlarged heads at its opposite ends of approximately the internal diameter of the casing, one of which heads is adapted to abut the inturned flange of the casing to prevent removal of the spindle through the flanged end of the casing, said last named head of the spindle having a reduced axial extension projecting exteriorly through the

adjacent end of the casing and provided with an opening, and a split spring ring through the said opening serving as an attaching means for the casing or container as a whole, and also functioning to normally prevent removal of the spindle or stem through the first mentioned end of the casing.

WILLIAM WARREN.
